Primary Examiner—Melvin B. Feifer*Assistant Examiner*—Lucy Lieberman*Attorney, Agent, or Firm*—Lawrence E. Evans, Jr.[57] **CLAIM**

The ornamental design for a liquid calibration container, as shown and described.

DESCRIPTION

FIG. 1 is an isometric view of the liquid calibration container showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

FIG. 1

FIG. 2

FIG. 3

FIG. 4

FIG. 5

FIG. 6

FIG. 7
